ROLLER CONVEYER CONSTRUCTION

Leonard Dodge Barry, Detroit, Mich.

Application August 22, 1949, Serial No. 111,626

10 Claims. (Cl. 193—35)

1

This invention relates to a construction for roller conveyors and in particular to a means of mounting the rollers therein.

One object of this invention is to provide a roller conveyor of sanitary construction which has a minimum of dirt collecting surface and which can be easily and quickly disassembled and reassembled for cleaning.

Another object is to provide an inexpensive roller conveyor which is of simple design, easy to assemble, and neat in appearance.

A more limited object is to provide a roller conveyor in which only two or at the most four pins or other fasteners are needed to hold a full length section of rollers in place.

Another definite object is to provide a simple form of roller conveyor in which the rollers can be inserted one at a time without shifting the shaft with respect to the roller or without the rollers dropping out of place because of spreading rigid side members too much upon placing other rollers.

Other objects are to provide protection for the grease holes and grease fittings when used on the shaft ends of the rollers, and to enable quick replacement of worn or faulty rollers. Other points of value may be found by one skilled in the understanding of roller conveyor manufacture and construction.

The invention is briefly a construction wherein shaft ends are inserted in strips that slide into place between structural members which have grooves thereon that receive the strips.

The drawing illustrates the invention and shows some variations to adapt for different rollers. Figure 1 is a view of a typical straight section in perspective. Figures 2, 3, 4, 5, and 6 are fragmentary cross sectional views showing modified forms. Figure 7 is a fragmentary cross sectional view of the construction shown in Figure 1. Figures 8 and 9 are expanded fragmentary views of a system of segmentation of a certain component.

Referring to the drawing and in particular to Figures 1 and 7; rollers represented by roller 1, complete with shaft and bearings, are shown with their shaft ends engaged in slots 2 in two retaining strips 4, each strip being slidably engaged in one of two grooves 5, each groove being on a parallel spaced structural side member 6. Members 6 are held in position relatively by means such as cross frame bracing F. The retaining strips 4 are shown in Figure 1 extended beyond side members 6 as during assembly to show the roller shaft engaged in slot 2 having a form to fit the roller shaft and of a depth to allow a flat

2

face 7 on the shaft to be positioned substantially flush with the top of retaining strip 4. The strips where engaged in grooves 5 are covered by groove 5. Likewise any roller shafts extending into the strips where engaged in grooves 5 are covered. The grease holes 8 and any fittings inserted therein are covered as well as the portion of face 7 within the groove. The flat face 7 engages with the top of the groove 5 and prevents the turning of the shaft. Strip 4 is held laterally from within against groove 5 by stationary ends 9 of the bearings of roller 1, providing a simple method of holding the strip 4 against a simple groove. Strips 4 are held from sliding in grooves 5 by tightening one set screw 10 in each structural side member against strip 4. The set screw is shown in the bottom of member 6 to retain the plane top and outward side faces of that structural member. More than one set screw could be used to hold strip 4. Any other suitable fastener such as a catch, pin, or bolt might be used instead of or in conjunction with the set screws.

The conveyor permits of easy slide in assembly. Having the side members 6 completed and cross braced with frame members F or otherwise held in place the strips 4 are inserted at one end of the grooves 5 and as the rollers are set in strips 4 one at a time the strips with rollers are slid within grooves 5.

Variations arise from different types of rollers, different qualities of construction, and alternative methods and shapes. Having set forth a typical construction permitting a slide in type assembly a few modified forms which might have been selected to typify the construction are pointed out as variations of the construction.

In Figure 2 roller 1a has external bearings 11a, only one of which is shown, the other end of the rollers being similar to the end shown. Bearing 11a is pressed into hole 3a instead of a slot in retaining strip 4a. Flange 12 on the bearing together with the back of structural member 6a retain the bearing laterally; though a press fit is also recommended. Side member 6a has two grooves 5a requiring less milling than one wide groove to accommodate the wide strip 4a. Grooves 5a perform the same function as groove 5. The bearing can be both press fit onto the shaft and inserted into strip 4a at the same time, permitting the rollers to be completely inserted one at a time even though strip 4a be rigid and have holes 3a that are not segmented as explained for Figures 8 and 9.

In Figure 3 side structural member 6b is an angle with a channel attached as shown. The channel furnishes the groove and is therefore

considered an adapting portion 13b of side member 6b. Strip 4b is a formed channel having holes 3b and should be flexible enough to permit assembly of the rollers in place one at a time as the strips 4b are pushed between the grooves 5b or strips 4b can be divided into segments.

In Figure 4 strip member 4c is held laterally from within by tapered members 7c providing the groove 5c on side member 6c. The taper is double that is V-shaped to hold the thin strip 4c from buckling and thereby prevent needless friction.

In Figure 5 roller 1d has an external bearing of the bushing or needle roller type press fit in a hole in channel strip 4d. The roller shaft can be turned down as shown so the bearing would not come out if it became loose. Strip 4d can be rigid and the rollers assembled therein as explained for Figure 2.

In Figure 6 strip 4e is held in place by grooving, a flange 14 being provided on member 7. This flange could be double that is V-shaped, differing from the taper only in angle and contour.

Figure 8 illustrates a segment and a fraction of strip 4g. Strip 4g need not be one piece the length of the conveyor section, but can be conveniently pieced together or can be sectioned at the roller shafts as shown. Thus with segment strips 4g, as shown Figure 8, a bearing can be inserted when the segments are separated and can be held when the segments engage in a groove around the bearing.

Figure 9 illustrates a segment and a fraction of strip 4h for holding a roller shaft 15. Short segments of strip 4h, as Figures 8 and 9 illustrate, can be rigid and used around a curve without rolling.

Having explained the constructions illustrated it can be pointed out that this construction applies equally well to curves and double roller sections. The strips if not required to be flexible can be braced and spaced together, but such construction is optional. Side members herein called structural members can be of varied cross section, and the grooves can be spaced in line along the structural members. The holes or slots in the retaining strips may be punched or milled recesses of less width than the strip. Rollers with through shafts are not a requirement: stub shafts can serve the same purpose. The roller may be made up of one or more roller wheels on a shaft, a common manufacture. The slots, holes, recesses, and segmented openings are herein given the term engagements. Under conditions as illustrated in Figures 4 and 6 that is whenever the retaining strips can be held in the structural member independent of the other parts stub shaft assemblies can be held in engagements along the strips. Stub shafts are herein designated as shafts held in only one frame either fixed or revolvable. Stub shafts support such things as short rollers, wheels, sprockets, and sometimes other items used in conveyors.

It is evident that there can be many and wide variations of this construction; therefore I do not wish to be limited to the few variations of this construction illustrated.

I claim:

1. A roller assembly for moving articles which comprises a plurality of rollers having shaft end projections, a plurality of parallelly spaced structural members, a plurality of slide retaining members, said structural members having grooves along their lengths which receive said slide retaining members in slidable relation, said slide

retaining members having engagements which receive said roller end projections.

2. A shaft assembly such as can be used in conveyors which comprises at least one structural member having a groove along its length, a slide retaining member which engages in said groove with sliding motion and is held therein, a plurality of engagements spaced along said slide retaining member, a plurality of shaft end members which engage in said engagements.

3. A shaft assembly such as can be used on conveyors which comprises a structural member having a plurality of grooves along its length, a slide retaining member which engages in said grooves and is held therein, a plurality of engagements spaced along said slide retaining member, a plurality of shaft ends which engage in said engagements on said slide retaining member.

4. A shaft assembly as claimed in claim 2 in which said slide retaining member is composed of segments having ends which when two such ends on different segments are brought end to end a said engagement is thereby provided.

5. A roller conveyor as claimed in claim 2 in which said groove is a channel member.

6. A roller conveyor as claimed in claim 3 the said grooves being double grooves and said retaining member being a channel the leg ends of which fit into said grooves.

7. A roller assembly as claimed in claim 1 in which said slide retaining members are held outwardly in said grooves by the ends of internal bearings of said rollers.

8. A shaft assembly as claimed in claim 3 said slide retaining member being strips having V-shaped top and bottom edges which cooperate with said grooves on said structural member to permit said strips to slide and be pushed without buckling in said grooves even though said strips be easily flexible.

9. A roller conveyor which comprises a plurality of rollers having shaft end projections, said projections having a substantially flat face thereon, a plurality of retaining strips having slot engagements spaced along and open to an edge thereon, a pair of parallelly and oppositely disposed structural members held in relative position by suitable means, said structural members having grooves along their lengths on the faces thereof which face each other, said retaining strips engaging in said grooves with slidable relation for assembly and disassembly, said strips receiving said roller projections when extended from said grooves, said projections being positioned in said slots with said flat face substantially flush with said edge, said projections being held when said strips therewith are properly slipped into said groove.

10. A shaft assembly as claimed in claim 2 said slide retaining member being a flexible strip whereby it can be partly inserted in said structural member and the remainder sprung to receive said shaft end members one at a time.
